UNITED STATES PATENT OFFICE.

GEORGE A. ARNOLD, OF BOSTON, MASSACHUSETTS, ASSIGNOR OF TWO-THIRDS TO
SOLOMON A. CAMPBELL, OF WALTHAM, MASSACHUSETTS.

AUTOMOBILE-HORN.

1,192,598.

Specification of Letters Patent. Patented July 25, 1916.

Application filed December 1, 1915. Serial No. 64,397.

To all whom it may concern:

Be it known that I, GEORGE A. ARNOLD, a citizen of the United States, and a resident of Boston, in the county of Suffolk and 5 State of Massachusetts, have invented certain new and useful Improvements in Automobile-Horns, of which the following is a specification.

This invention relates to certain improvements in pneumatically operated warning signals of a type particularly adapted for use on motor vehicles. In the common form 10 of instruments of this character there is employed a bulb which, upon being compressed, forces the air past a reed or other vibratory sound producing member. Such instruments operate to give but a single signal for each compression of the bulb.

As an important feature of my invention, 15 I provide air compressing means including a cylinder and a reciprocatory air compressing piston and connections to the sound producing mechanism whereby a warning signal or sound may be produced by a movement of said piston in either direction and 20 whereby two different sounds may be produced alternately and in rapid succession by the rapid reciprocation of said piston, both of the sounds being directed forwardly. 25 This is preferably accomplished by a plurality of sound producing elements, one operating to produce one sound when the piston is moved in one direction and another operating to produce a different sound when 30 said piston is moved in the opposite direction.

Various different embodiments of my invention may be designed and the various details may be changed within the spirit of my 35 invention and without departing from the scope of the appended claims.

Reference is to be had to the accompanying drawings in which I have illustrated two embodiments and in which similar reference characters indicate corresponding 45 parts in the several views.

In these drawings, Figure 1 is a central 50 longitudinal section through a portion of a warning signal constructed in accordance with my invention; Fig. 2 is an end view of the form shown in Fig. 1; and Fig. 3 is a side view of a horn similar to that shown in Fig. 1, but operated by a motor.

In the specific form of horn shown in

Figs. 1 and 2, the air compressing means 55 includes a cylinder 10 having cylinder heads 11 and 12 secured thereto in any suitable manner. Within the cylinder is a piston 13 provided with suitable gaskets whereby air may be put under compression in either end 60 of the cylinder by a movement of the piston toward that end. The cylinder head 11 has an inlet port 14 controlled by a check valve 15 and has an outlet port 16 to which is connected a tube 17 leading to any suitable form 65 of horn or resonator. The opposite head 12 of the cylinder has an inlet port 18 controlled by a check valve 19 and has an outlet port 20 from which extends a tube 21 leading to a horn or resonator which may 70 be a different one from that to which the tube 17 is connected. Within the tubes 17 and 21 are provided the two sound producing members 22 and 23 which are here illustrated rather conventionally as reeds of the 75 type used in connection with the ordinary bulb horn. These two reeds may in some cases be identical and serve to produce similar sounds, but preferably they are different in construction, size or proportions, so that 80 the sound produced by one will be of a higher pitch than that produced by the other. The notes produced by the two sound producing members may be at any predetermined distance apart in the musical scale 85 so that the two notes will bear a predetermined musical relationship to each other, such for instance as making them an octave apart, or each may be selected without respect to the other. 90

It will be noted that when the piston 13 is moved in one direction, for instance toward the right hand from the position shown in Fig. 1, the check valve 19 will be closed and the air in the right hand end of 95 the cylinder will be forced through the outlet 20 while the check valve 15 will open and air will be drawn into the left hand end of the cylinder. Upon reversing the direction 100 of movement of the piston, the check valve 19 will open and air will be forced out through the tube 17.

By rapidly reciprocating the piston, a substantially continuous delivery of air will be produced, first past one sound producing 105 member and then past the other so that a substantially continuous sound will be produced of the same pitch or alternate high

and low pitch, dependent upon the character of the sound producing members. As a simple means for securing this rapid reciprocation of the piston, I have illustrated the 5 piston as being provided with a piston rod 24 extending through the cylinder head 12 and connected to a lever 23. The lever is illustrated as being pivoted intermediate its ends on a bracket or arm 26 rigid with the 10 cylinder. One end of the lever has a knob or handle 27 which may be readily grasped by the operator while the opposite end is connected to the end of the piston rod. The 15 connections between the lever and the piston rod, or the connections between the lever and the supporting bracket 26 include means for permitting the piston rod to move in a straight line. Merely as an example of such connection, I have illustrated the piston rod 20 as being provided with a head 28 with a transverse slot 29 therein receiving a pin 30 carried by the lever adjacent its end. I do not wish to be limited to this specific construction or to this particular mechanism 25 for reciprocating the piston. The lever illustrated is one of the first class which permits the range of movement of the handle to be greater or less than the range of movement of the piston in accordance with 30 the relative lengths of the lever portions at opposite sides of the fulcrum.

I have illustrated the inlets and outlets from the cylinder in the cylinder heads, but it is of course evident that this specific location is not essential. The various other details which I have illustrated are not important except as they are pointed out and defined in the claims.

In Fig. 3, I have shown a horn similar to 40 that shown in Fig. 1 except in regard to certain details including the driving mechanism. Instead of reciprocating the piston rod by means of a hand lever, I have illustrated one form of power transmitting connections to an electric motor 35. The motor is illustrated as being supported on a bracket 36 connected to the cylinder head 11 although it is of course evident that the motor might be supported or mounted in various 45 different ways. The bracket, or support 37, which I have illustrated serves as a means for securing the cylinder or air compression chamber to a part of a motor vehicle or any other suitable supporting surface. The motor is illustrated as having a worm 38 on the armature shaft and meshing with a worm wheel 39. The worm wheel has a pin 30 engaging in the slot 29 of the transverse head of the piston rod. The head 28^a is here 50 shown as somewhat longer than the head shown in Fig. 1, but this length is dependent upon the eccentricity of the pin 30 and the length of the stroke of the piston. The motor is of a cylindrical high speed type adapted to be operated from suitable dry cells or 55

storage batteries carried on the vehicle, as for instance those used for energizing the ignition circuit of the engine.

Each revolution of the worm wheel gives a complete back and forth movement of the piston, and the pitch and relative diameters of the worm and worm wheel are such that the motor while running at normal high speed will reciprocate the piston with sufficient rapidity to produce the sound. The 75 worm wheel may be made comparatively heavy so as to have a certain fly wheel effect if desired.

The tubes 17 and 21 may each have a sound producing member therein similar to 80 those shown in Fig. 1 and the two may be connected to the same resonator 40 as shown in Fig. 3.

If desired, only a single sound producing member may be employed and may be positioned beyond the point of junction of the two tubes 17 and 21 so that air discharged from the air compressing device upon either stroke of the piston will pass through the same sound producing device and a continuous, or substantially continuous, and uniform tone will be produced while the motor is running. The circuit of the motor may be closed by an ordinary push button mounted on the steering wheel or in any 90 other manner as is common in motor operated diaphragm horns.

I have shown the resonator of Fig. 3 as being substantially straight although it may be curved or coiled as employed in many 100 common forms of bulb operated horns.

Having thus described my invention, what I claim as new and desire to secure by Letters Patent is:

1. A warning signal including a cylinder 105 having separate valve controlled inlets at opposite ends and separate outlets at opposite ends of said cylinder, vibratory sound producing devices connected to said outlets, a piston within said cylinder adapted upon 110 reciprocation to deliver air alternately through said outlets to operate said sound producing devices, a bracket carried by said cylinder, a lever pivotally mounted on said bracket, a piston rod connected to said piston, and slot and pin connections between 115 said piston rod and one end of said lever.

2. A warning signal including a cylinder having separate valve controlled inlets at opposite ends and separate outlets at opposite 120 ends, a tube extending from one of said outlets in the general direction of the axis of the cylinder, a tube extending from the other of said outlets and including an elbow portion and a straight portion extending in the 125 same general direction as said first mentioned tube, separate vibratory sound producing devices within said tubes, a piston within said cylinder and means for reciprocating said piston to deliver air past said 130

sound producing devices alternately and deliver the sound from both in the same general direction.

3. A warning signal including a cylinder, 5 a piston therein, separate valve controlled air inlets permitting the admission of air to said cylinder at either side of said piston, separate outlet tubes connected to opposite ends of said cylinder, one of said tubes including an elbow and both of said tubes extending in the same general direction and both including vibratory sound producing devices, a bracket rigid with said cylinder adjacent the upper side thereof and an upwardly extending lever pivoted intermediate of its ends on said bracket and having a handle at its upper end and connections at its lower end with said piston.

4. A warning signal including a cylinder, 10 a piston therein, separate outlet tubes con-

nected at opposite ends of said cylinder, vibratory sound producing mechanism operated by the delivery of air through said tubes, a bracket extending rearwardly from one end of said cylinder adjacent the upper 25 side thereof and an upwardly extending lever, pivoted intermediate of its ends on said bracket and having its lower end connected to said piston, and its upper end presenting a handle whereby said piston may 30 be reciprocated and the signal operated by the delivery of air through either of said tubes.

Signed at Waltham, in the county of Middlesex and State of Massachusetts, this 29th 35 day of November, A. D. 1915.

GEORGE A. ARNOLD.
